Primary Examiner — Selina Sikder(74) *Attorney, Agent, or Firm* — Jenkins, Wilson, Taylor & Hunt, P.A.(57) **CLAIM**

The ornamental design for a light emitting diode, as shown and described.

DESCRIPTION

FIG. 1 is a top perspective view of an LED showing our design;

FIG. 2 is a top view thereof;

FIG. 3 is a front view thereof;

FIG. 4 is a rear view thereof;

FIG. 5 is a bottom view thereof opposite the view of FIG. 2;

FIG. 6 is a side view thereof;

FIG. 7 is an opposing side view thereof; and,

FIG. 8 is a back perspective view thereof.

The outermost circle shown in broken lines in FIGS. 1 and 2 define the bounds of the claimed design and form no part of the claimed design. The remaining broken lines in FIGS. 1-8 are shown for illustrative purposes only and form not part of the claim design.
